[57] CLAIM

The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of the design of FIG. 1, the only difference being in the horizontal angle of the skirt;

FIG. 6 is a side elevational view of the design of FIG. 1, the only difference being in the near vertical angle of the skirt; FIG. 7 is a side elevational view of the design of FIG. 1, the only difference being in the downward angle of the skirt; FIG. 8 is a side elevational view of a second embodiment of the design of FIG. 1, the only difference being in the height of the base; FIG. 9 is a side elevational view of a third embodiment of the design of FIG. 1, the only difference being in the height of the base; FIG. 10 is a top plan view of a fourth embodiment of the design of FIG. 1, the only difference being in the size of the skirt; FIG. 11 is a top plan view of a fifth embodiment of the design of FIG. 1, the only difference being in the size of the skirt; FIG. 12 is a perspective view of a sixth embodiment of our new flower pot cover design; FIG. 13 is a side elevational view thereof; FIG. 14 is a top plan view thereof; FIG. 15 is a bottom plan view thereof; FIG. 16 is a side elevational view of the design of FIG. 12, the only difference being in the horizontal angle of the skirt; FIG. 17 is a side elevational view of the design of FIG. 12, the only difference being in the near vertical angle of the skirt; FIG. 18 is a side elevational view of the design of FIG. 12, the only difference being in the downward angle of the skirt; FIG. 19 is a side elevational view of a seventh embodiment of the flower pot cover design, the only difference over FIG. 12 being in the height of the base; FIG. 20 is a side elevational view of an eighth embodiment of the flower pot cover design, the only difference over FIG. 12 being in the height of the base;

FIG. 21 is a top plan view of a ninth embodiment of the flower pot cover design, the only difference over FIG. 12 being in the size of the skirt; FIG. 22 is a top plan view of a tenth embodiment of the flower pot cover design, the only difference over FIG. 12 being in the size of the skirt; FIG. 23 is a perspective view of an eleventh embodiment of our new flower pot cover design; FIG. 24 is a side elevational view thereof; FIG. 25 is a top plan view thereof; FIG. 26 is a bottom plan view thereof; FIG. 27 is a side elevational view of the design of FIG. 23, the only difference being in the horizontal angle of the skirt; FIG. 28 is a side elevational view of the design of FIG. 23, the only difference being in the near vertical angle of the skirt; FIG. 29 is a side elevational view of the design of FIG. 23, the only difference being in the downward angle of the skirt; FIG. 30 is a side elevational view of a twelfth embodiment of the flower pot cover design, the only difference over FIG. 23 being in the height of the base; FIG. 31 is a side elevational view of an thirteenth embodiment of the flower pot cover design, the only difference over FIG. 23 being in the height of the base; FIG. 32 is a top plan view of a fourteenth embodiment of the flower pot cover design, the only difference over FIG. 23 being in the size of the skirt; and, FIG. 33 is a top plan view of a fifteenth embodiment of the flower pot cover design, the only difference over FIG. 23 being in the size of the skirt.

UNITED STATES PATENT AND TRADEMARK OFFICE
CERTIFICATE OF CORRECTION

PATENT NO. : Des. 384,003
DATED : September 23, 1997
INVENTOR(S) : Donald E. Weder et al.

It is certified that error appears in the above-identified patent and that said Letters Patent is hereby corrected as shown below:

Cover Sheet, under Related U.S. Application Data, Section [60], line 1, please delete "Mar. 17, 1993", and substitute therefor --Mar. 19, 1993--.

Signed and Sealed this
Tenth Day of February, 1998
